UNITED STATES PATENT OFFICE.

WILLIAM H. POWERS AND BENJAMIN F. POWERS, OF CLEVELAND, OHIO.

CORRUGATED RIDGE-CAPPING FOR BUILDINGS.

SPECIFICATION forming part of Letters Patent No. 365,096, dated June 21, 1887.

Application filed October 27, 1886. Serial No. 217,353. (No model.)

To all whom it may concern:

Be it known that we, WILLIAM H. POWERS and BENJAMIN F. POWERS, of Cleveland, in the county of Cuyahoga and State of Ohio, 5 have invented a certain new and Improved Corrugated Ridge-Capping for Buildings, consisting of two sections or parts secured together by nuts or bolts; and we do hereby declare that the following is a full, clear, and 10 complete description thereof.

The nature of our invention relates to a crimped or corrugated angular strip of sheet or plate metal with a tubular or cylindrical ridge riveted to the junction of the angle of 15 the sheet and extending the entire length of the capping. The attachment of the tubular ridge to the apex or junction of the angle is so made as to admit of the expansion and contraction longitudinally of ridge-capping sections. 20 The angular strip is crimped along the ridge or point of the angle and sides to prevent the sheet from cracking or breaking, while the tubular ridge insures strength and stability to the angular sheet, as hereinafter 25 fully set forth.

Figure 1 is a top view of the ridge-capping; Fig. 2, a side view, and Fig. 3 is a transverse section.

Like letters of reference refer to like parts 30 in the several views.

The ridge-capping consists of two parts or sections—the corrugated and angular cap A and the tubular ridge B—which are secured together by screw-bolts or rivets C, Figs. 1 35 and 2. The ridge B forms a tube along the entire length of the capping, the ends of which are united by a lap-joint connection, or otherwise secured together. The purpose of the tubular ridge is to give strength to the cap or 40 capping A, which is essential when the entire roof is of iron and a large or wide ridge-capping required. In a slate or flat sheet roof it is also of material advantage and forms an 45 ornamentation to the roof-ridge.

By making the capping first separate from 50 the ridge B the crimps D can be pressed into the top part of the capping, (which cannot be done in case the ridge B and capping A are in one piece,) which is of material advantage

making or when in use. Along the sides of the capping are formed crimps or corrugations E. These corrugations may be changed to correspond with and adapted to the form of the roof on which is to be the ridge-capping, as indicated at F, which represents a part of a metal-plate roof, Fig. 3. As the ridge B is of a separate section from the capping A, the expansion and contraction transversely by climatic influence of one section 55 does not in use affect the integrity of the other. As the rivets or their equivalents pass through slots in the sections A and B in line with the capping, the sections are secured together, and also admit by means of the slots a free 60 expansion and contraction longitudinally of the sections. The tubular form of the ridge admit of its extension and contraction longitudinally by reason of the yielding attachment and at right angles without affecting the cap- 65 ping A, and the crimps at D relieve the sheet from buckling up when the corrugations E and crimps D are pressed out on the sheet. The crimps D and corrugations E compensate 70 or so neutralize the extension and contraction 75 of the sheet as to prevent it cracking or buckling up by the strain of the weather to which it is subjected. This is essentially the case when a large metallic surface is exposed.

In case of injury to one part of the ridge- 80 capping, the injured section may be removed and a new one substituted without displacing the entire ridge-capping. This construction admits of the ridge-capping being made of one continuous unbroken length by inserting 85 a series of tubular ridges B, one into the other, and lapping the capping A onto each other in such way as to break joints at connections with the ridges B and capping A—that is to say, the lapping of the capping need 90 not be in transverse line with the connection of the tubular ridges.

What we claim as our invention, and desire 95 to secure by Letters Patent, is—

1. A metallic ridge-capping for buildings 95 and other similar purposes, consisting of the corrugated section A, in combination with the tubular ridge B, constructed as described, and connected together in the manner substantially as set forth.

2. In combination with a corrugated or crimped sheet-metal roof, the angular section A, having corrugated sides adapted to lap on the corresponding forms of a metal roof, said 5 angular section terminating in corrugations D at or near the apexial angle between the corrugated side sections, substantially as and for the purpose described.

In testimony whereof we affix our signatures in presence of two witnesses.

WILLIAM H. POWERS.
BENJAMIN F. POWERS.
